UNITED STATES PATENT OFFICE.

WILLIAM S. FARRINGTON, OF SYRACUSE, NEW YORK.

DESIGN FOR AN EGG-CUP.

SPECIFICATION forming part of Design No. 24,983, dated December 17, 1895.

Application filed April 22, 1895. Serial No. 546,766. Term of patent 14 years.

To all whom it may concern:

Be it known that I, WILLIAM S. FARRINGTON, of Syracuse, in the county of Onondaga, in the State of New York, have invented a new and useful Design for Egg-Cups, of which the following is a specification, reference being had to the accompanying drawings, showing a part thereof.

Figure 1 is an elevation of an egg-cup embodying my design; and Fig. 2, a vertical section of the same, taken on line 2 2, Fig. 1, these views being deemed necessary to fully illustrate the design.

The leading features of my design consist in a substantially circular body having a contracted upper end formed with a substantially flat top face, and having the outer faces of diametrically-opposite parts formed substantially parallel; a central portion formed with an annular shoulder at the base of said upper end, and having the upper ends of outer faces of diametrically-opposite parts formed substantially parallel and the lower ends of said faces extended toward each other, and a contracted lower end having the outer faces of diametrically-opposite parts disposed in planes forming, essentially, corresponding sections of substantially elliptical planes.

A is the substantially circular body of my design, and a, a' and a² are, respectively, its upper and lower ends and its central portion. The upper end a is of less diameter than the central portion a², its top face a³ is formed substantially flat, and the upper portion of its upright outer face is formed with spiral ribs and grooves a⁴ a⁵, and the lower portion

of said upright face is substantially plain. The outer faces a⁷ a⁷ of diametrically-opposite parts of the upper end a are substantially parallel, and the central portion of said end 40 is formed with an annular shoulder a⁸.

The central portion a² of the body A is formed with an annular top shoulder a⁹ projecting from the plain lower portion a⁶ of the upper end a, and the upper ends a¹⁰ of outer 45 faces of diametrically-opposite parts of said central portion are formed substantially parallel, and the lower ends a¹¹ of said faces are extended toward each other. The central portion a² is also provided with ornamentation a¹², representing flowers, leaves, &c., or other objects or designs. The lower end a' is decreased in diameter toward its base, and the outer faces of diametrically-opposite parts thereof are disposed in planes forming, essentially, 50 corresponding sections of substantially elliptical planes.

My design is very pleasing in appearance, and adds greatly to the salability of the egg-cup.

What I claim is—

The design for an egg cup, substantially as herein shown and described.

In testimony whereof I have hereunto signed my name, in the presence of two attesting witnesses, at Syracuse, in the county of Onondaga, in the State of New York, this 18th day of April, 1895.

WILLIAM S. FARRINGTON.
